RELAY

Walter Schaelchlin, Wilkinsburg, Pa., assignor to
Westinghouse Electric & Manufacturing Company, a corporation of Pennsylvania

Application June 16, 1930, Serial No. 461,268

7 Claims. (Cl. 200—91)

My invention relates to relays and particularly to relays, of the electromagnetic type, adapted for use in alternating-current systems.

Sensitive electromagnetic relays, built according to the teachings of the prior art, have generally been unsatisfactory when energized by an alternating current. The cyclical alternations of the current wave cause the magnet armature to vibrate at a frequency corresponding to the frequency of the alternating current. The vibration of the armature is transmitted to the contact members of the relay which results in arcing and burning of the contact members. The vibration may be severe enough to produce an open circuit between the contact members, resulting in the erratic operation of the system in which the relay is connected.

An object of my invention, generally stated, is to provide a sensitive electromagnetic relay which shall be simple and efficient in operation, and which may be readily and economically manufactured.

A more specific object of my invention is to prevent vibration of the contact members of a relay when the magnet coil is energized by an alternating current.

For a fuller understanding of the nature and objects of the invention, reference may be had to the following detail description, taken in conjunction with the accompanying drawing, in which:

Figure 1 is a view, partly in side elevation and partly in section, of a relay constructed in accordance with my invention;

Fig. 2 is a view, partly in front elevation and partly in section, of the relay, and

Fig. 3 is a view, in side elevation, of a modification of the invention.

Referring now to the drawing, a relay 6, embodying my invention, is shown mounted on an insulating panel 7. The relay 6 comprises an electromagnet 8 having a primary coil 9 and an inductively wound secondary coil 11. An armature 12 is pivotally mounted on a bracket 10 and disposed to be actuated by the coil 9. Connecting studs 13 and 14 are provided for the windings 9 and 11, respectively.

In order to provide a relay which is sensitive in operation, the electromagnet 8 should preferably be of the air core type, although a magnet having an iron core may be utilized if desired. The sensitivity of the relay may be increased by mounting the armature 12 on ball bearings 15 to reduce friction and by so constructing the

armature 12 that it will be balanced on its pivotal axis.

A spring 16 is provided to normally bias the armature 12 to the position shown in the drawing. The tension of the spring 16 may be varied by means of an adjusting screw 17, thereby changing the value of current required in the primary coil 9 in order to actuate the armature 12. The value of current at which the armature 12 will be actuated may also be governed by connecting a variable resistor across the terminals 14 of the secondary winding 11. The flux induced in the coil 11 opposes the flux of the primary coil 9. A graduated scale 18 and a pointer 19 are provided to assist in so adjusting the spring 16 that the armature 12 will be actuated when a predetermined value of current flows through the coil 9.

In order that a movable contact member 20, which is disposed to engage a fixed contact member 21, will not be affected by the cyclical vibration of the armature 12, caused by the varying flux in the electromagnet 8 when the coil 9 is energized by an alternating current wave, the contact member 20 is mounted on a separate mechanical system from the armature 12. In the preferred embodiment of my invention, illustrated in Figs. 1 and 2, the contact member 20 is mounted on a rectangular weight 22, which is pivotally supported on a pin 23. The pin 23 extends through the vertical axis of the weight 22 and is supported at the bottom in a cup bearing 24 and at the top by a sleeve bearing 25. A point may be provided on the bottom of the pin 23 which rests in the cup bearing 24 in order to reduce the friction to a minimum.

It will be seen that the weight 22 may be oscillated about its pivotal axis to cause the contact member 20, which is mounted near one end of the rectangular weight 22, to engage the fixed contact member 21, which is mounted on a bracket 26. If it is desired, another contact member may be mounted near the other end of the rectangular weight 22 which will engage an additional fixed contact member. The two sets of contact members will, therefore, be alternately closed and opened as the weight 22 is oscillated about its pivotal axis.

In order that the cyclical vibration of the armature 12 will not be transmitted to the contact member 20, the weight 22 is connected to the armature 12 by a spring 27. Since the spring 27 is fastened near one end of the weight 22, the weight will be oscillated about its pivotal axis as the armature 12 is actuated by the coil 9.

With a view to still further preventing the con-

tact member 20 from being affected by the cyclical vibrations of the armature 12, the mass of weight 22 may be made such that the natural period of vibration of the weight 22 will be different from the period of vibration of the armature, produced by the frequency of the alternating current by which the coil 9 is energized. Therefore, the weight 22 will not respond to the frequency of the cyclical vibration of the armature 12.

10 In order that the contact member 20 will not be affected by any vibration of the weight 22, which may be caused by vibration of the supporting panel 7, the contact member 20 is mounted on one end of a flexible spring 28, the other end of which is connected to the weight 22.

15 When the coil 9 is energized by a predetermined value of current, the armature 12 is actuated about its pivotal axis, thereby creating a tension in the spring 27. Accordingly, the weight 22 is actuated by the spring 27 and the contact member 20 engages the contact member 21. By connecting the contact members in an electrical circuit, through connecting studs 29, switching operations may be performed to control the operation of electrical apparatus, as is well known in the art.

20 By preventing vibration of the contact members of the relay, arcing and burning of the contact members, which results if the contact members vibrate while carrying current, is reduced and the life of the contact members is greatly increased.

25 A modification of the invention is illustrated in Fig. 3, in which parts performing the same function as those shown in Figs. 1 and 2 are designated by the same reference characters.

30 It will be observed that the principal differences between the two relays are the construction and method of mounting of the weight 22. In Fig. 3 the weight 22 is shown as being cylindrical and is mounted on a shaft which extends through its horizontal axis instead of through its vertical axis. The springs 16 and 27 are also shown in different positions, but they perform the same functions as in the above-described relay.

35 While I have described the invention as being applicable to relays which are energized by alternating current, it will be readily understood by those familiar with the art that relays constructed in accordance with my invention, as herein described, may also be energized by direct current and satisfactory operation obtained.

40 Since many modifications may be made in the apparatus and arrangement of parts without departing from the spirit of my invention, I do not wish to be limited other than by the scope of the appended claims.

45 I claim as my invention:

1. In a relay, in combination, a contact member carried by a pivotally mounted weight, an armature disposed to oscillate the weight, a coil disposed to actuate the armature when energized, the mass of the weight being substantially greater than that of the armature, and means interposed between the contact member and the armature to prevent the vibration of the armature being transmitted to the contact member.

50 2. In a relay, in combination, an electromagnet comprising a coil and an armature disposed to be actuated by the coil, a contact member mounted

5 on a movable weight of a substantially greater mass than the armature, said weight being disposed to be oscillated by the armature, and a resilient member interposed between the armature and the weight to prevent the transmission of the vibration of the armature to the contact member.

10 3. In a relay, in combination, contact members disposed to be actuated into and out of engagement to perform switching operations, a pivotally mounted armature, a coil disposed to actuate the armature when energized, a pivotally mounted weight of a substantially greater mass than the armature for supporting one of the contact members, said weight being disposed to be actuated by the armature to actuate the contact members into and out of engagement, and resilient means for connecting the armature to the weight, thereby preventing the transmission of the armature vibration to the contact members.

15 4. In a relay, in combination, contact members disposed to be actuated into and out of engagement to perform switching operations, a pivotally mounted armature, a coil disposed to actuate the armature when energized, a spring disposed to normally bias the armature to a predetermined position, means for varying the tension of said spring, a pivotally mounted weight of a substantially greater mass than the armature for supporting one of the contact members, said weight being disposed to be actuated by the armature to actuate the contact members into and out of engagement, and resilient means for connecting the armature to the weight, thereby preventing the transmission of the armature vibration to the contact members.

20 5. In a relay, in combination, a magnet coil, a pivotally mounted armature disposed to be actuated by the coil when energized, a pivotally mounted weight disposed to be actuated by the armature, resilient means for connecting the armature to the weight, a contact member disposed to be actuated by the weight, the mass of said weight being such that it is not affected by the cyclical vibration of the armature when the magnet coil is energized by an alternating current.

25 6. In a relay, in combination, a magnet coil, a pivotally mounted armature disposed to be actuated by the coil when energized, a pivotally mounted weight disposed to be actuated by the armature, resilient means for connecting the armature to the weight to prevent the vibration of the armature being transmitted to the weight, a contact member disposed to be actuated by the weight, resilient means for connecting the contact member to the weight, whereby the contact member is not affected by the vibration of weight.

30 7. In a relay, in combination, an electromagnet comprising a coil and an armature disposed to be actuated by the coil, a movable weight disposed to be oscillated by the armature, a contact member mounted on the movable weight, and resilient means for connecting the armature to the weight, the mass of the weight being such that the natural period of vibration of the weight is different from the cyclical vibration produced in the armature when the coil is energized by an alternating current, whereby the weight is not affected by the cyclical vibration of the armature.

35 WALTER SCHAEELCHLIN.
